(57) **CLAIM**

The ornamental design for a image analyzer, as shown and described.

DESCRIPTION

FIG. 1 is a front perspective view of an image analyzer showing our new design;

FIG. 2 is a top, right side, front perspective view thereof;

FIG. 3 is a rear, bottom, left side perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right side elevational view thereof;

FIG. 9 is a left side elevational view thereof;

FIG. 10 is a front perspective view showing a condition in which the cover is opened thereof;

FIG. 11 is a top, right side, front perspective view showing a condition in which the cover is opened thereof;

FIG. 12 is a rear, bottom, left side perspective view showing a condition in which the cover is opened thereof;

FIG. 13 is a front elevational view showing a condition in which the cover is opened thereof;

FIG. 14 is a rear elevational view showing a condition in which the cover is opened thereof;

FIG. 15 is a top plan view showing a condition in which the cover is opened thereof;

FIG. 16 is a bottom plan view showing a condition in which the cover is opened thereof;

FIG. 17 is a right side elevational view showing a condition in which the cover is opened thereof; and,

FIG. 18 is a left side elevational view showing a condition in which the cover is opened thereof.
